RIVET CONSTRUCTION

Lars Hedström, Orange, N. J.

Application October 18, 1941, Serial No. 415,506

13 Claims. (Cl. 85—38)

This invention relates to rivet construction. One of the objects of this invention is to provide a rivet construction which is simple, thoroughly practical, and durable in use. Another object is to provide a construction of the above character which can be securely set in a hole, only one end of which is accessible to the workman setting the rivet. Another object of this invention is to provide a construction of the above character, the manufacture of which will be economical both from the standpoint of labor and materials used. A further object is to provide a construction of the above character which may be quickly and easily secured in place by a single workman. A still further object is to provide a construction of the above character in which the structural elements are so disposed as to attain a high degree of strength without heavy construction. Still another object is to provide a construction of the above character which will be sturdy and well able to withstand heavy strains. Other objects will be in part obvious and in part pointed out hereinafter.

The invention accordingly consists in the features of construction, combinations of elements, and arrangements of parts, all as will be illustratively described herein and the scope of the application of which will be indicated in the following claims.

In the accompanying drawings in which are shown several of the various possible embodiments of this invention,

Figure 1 is a perspective view of a rivet embodying the present invention;

Figure 2 is a side elevation of the rivet shown in Figure 1 in position within a hole before being set;

Figure 3 is a side elevation of the rivet shown in Figure 2 after being set;

Figure 4 is a top plan view, on a reduced scale, of a sheet metal blank used in the construction of the rivet shown in Figures 1 through 3;

Figures 5, 6, 7, and 8 are side elevations, on a reduced scale, showing steps followed in the forming of the rivet shown in Figures 1 through 3;

Figure 9 is a side elevation, on a reduced scale, of a completed rivet;

Figure 10 is a section taken on the line 10—10 of Figure 9;

Figure 11 is a perspective view of another embodiment of the rivet shown in Figure 1;

Figure 12 is a side elevation of the rivet shown in Figure 11 in position within a hole before being set;

Figure 13 is a side elevation of the rivet shown in Figure 12 after being set;

Figure 14 is a perspective view of another embodiment of the rivet shown in Figure 1;

Figure 15 is a vertical section of the rivet shown in Figure 14, the rivet being in position within a hole before being set;

Figure 16 is a vertical section of the rivet shown in Figure 15 after the rivet is set;

Figure 17 is a top plan view of the head of the rivet shown in Figure 16;

Figure 18 is a perspective view of portions of the construction shown in Figure 15 showing means for locking the rivet in a set position;

Figure 19 is a horizontal section taken on the line 19—19 of Figure 11; and

Figure 20 is a horizontal section taken on the line 20—20 of Figure 12.

Similar reference characters refer to similar parts throughout the several views of the drawings.

As conducive to a clearer understanding of certain features of this invention, it might here be pointed out that in the construction of airplanes, radios, and other devices in which rivets are used, it has proved extremely difficult in many instances and impossible in others to use the standard type of rivet. The main cause for the difficulties encountered lies in the inaccessibility, in many instances, of the inner end of the rivet which either prevents or makes it extremely difficult to form a head on that end of the rivet. In many instances, screws, expanding bolts, and other threaded securing members have

been used in place of rivets. These have not proved satisfactory, however, because under the strains and vibrations existing in many places, such as in airplanes, there is always the possibility that a threaded securing member may loosen, which, in the case of airplanes and in many other instances, may have very serious consequences. Another difficulty with this type of securing element lies in the time consumed in setting it which because of the extremely large number of securing elements used in certain instances such as in planes, is a major factor.

Thus, rivets are the most satisfactory form of securing element in planes and in many other places because of their strength, permanence, and ease of setting. It is accordingly another object of this invention to provide a rivet construction which may be easily and quickly set in places where the inner end of the rivet is extremely difficult to reach or is inaccessible.

Referring now to the drawings and to Figure 1

in particular, the rivet construction shown includes outer stationary and inner movable portions. The outer portion of the rivet is held during setting of the rivet in a substantially stationary position with respect to the object in which the rivet is being set and includes sections 10 and 11, while the inner portion, which moves as the rivet is being set, includes sections 12, 13, 14, and 15. The outer and inner portions of the rivet are interconnected through the rivet's head and feet, generally indicated at 16, 17, and 18, respectively, in such a manner that when the movable portion of the rivet is moved downwardly by striking head 16, the outer and inner portions of the rivet coact to cause the feet 17 and 18 to spread (Figures 2 and 3) and firmly grip the object being riveted, such as plates 19 and 20, between the head and feet of the rivet, all as will be described hereinafter.

Referring now to Figures 4 through 10, the rivet shown in Figures 1 through 3 is preferably formed from a flat metal blank generally indicated at 21 (Figure 4). This blank is first preferably cut and scored on the full and dotted lines, respectively, shown on the blank in Figure 4, dividing the blank into the head, feet, and movable and stationary portions of the rivet. The portions of the blank to the left of the score line 22a and between score lines 23a and 24 form the movable sections 12, 13, 14 and 15 (Figure 1) of the rivet, the portion between score lines 22c and 23a (Figure 4) form the stationary (Figure 1) sections 10 and 11, and the remainder of the blank forms the head and feet of the rivet as best shown in Figures 5, 6 and 7. After cutting and scoring, the blank is placed in a press to crimp the blank at transverse score lines 22a, 22b, 22c, 23a, 23b, 23c and 24 as shown in Figure 5. Thus, the portions of the blank between score lines 23a and 23c and lines 22a and 22c are bent downwardly as viewed in Figure 5 to form portions of the head and feet of the rivet, respectively, and the feet reinforcing elements 25 and 26 at the right-hand end of the blank are bent upwardly with respect to sections 12 and 15 at substantially the same angle that the portion of the blank between lines 22b and 22c is bent downwardly.

After the blank is pressed into the shape shown in Figure 5, the right-hand portion of the blank, as viewed in Figure 5, is bent on score line 23c on top of the center portion of the blank (Figure 6) so that sections 12 and 15 are substantially parallel to sections 10 and 11. Next, the outer end of the blank is bent on score line 22b over the center portion (Figure 7) of the blank so that it is superimposed on sections 10, 11, 12 and 15. When the blank is folded into this position, longitudinal score lines 27, 28 and 29 (Figure 4) are in alignment with each other, and the construction shown in Figure 7 is folded through 180° on these lines so that movable sections 13 and 14 are face to face. An intermediate stage of this step is shown in Figure 8 in which the fold is halfway completed, sections 10, 12 and 13 being positioned at 90° angles to sections 11, 14 and 15. When this fold is completed, sections 10, 11, 12, 13, 14 and 15 are in substantially parallel relationship to each other, and section 10 coacts with section 11, section 12 with section 15, and section 13 with section 14 because of their connection along score lines 27, 28 and 29, respectively (Figures 4, 9 and 10).

As best seen by a comparison of Figures 4 and 9, the portions of the blank between score lines

22a and 22c and the reenforcing elements 25 and 26 form the legs 17 and 18 of the rivet, while the portions of the blank between score lines 23a and 23c, in conjunction with portions of sections 12, 13, 14 and 15, form the rivet's head. Also, from these figures it may be seen that the distance between transverse score lines 22a and 22b and between lines 23b and 23c is substantially greater than the distance between lines 22b and 22c and 23b. This makes the inner legs 30 and 31 (Figure 9) of feet 17 and 18 of substantially greater length than the outer legs 32 and 33, and the upper head portions 34 and 35 of greater length than the lower head portions 36 and 37. These members are preferably constructed in this manner both to aid in setting the rivet and to add to its strength after it is set, all as will be disclosed hereinafter.

In operation, a rivet of this type is placed in a hole 38 (Figure 2) extending through plates 19 and 20. When the rivet is in position in the hole, the head 16 is struck. As the lower portions 36 and 37 of the head are in contact with the edge of hole 38, they prevent downward movement of the stationary sections 10 and 11 and of the outer legs 32 and 33 of the feet. Sections 12, 13, 14, and 15, however, move downwardly, and as they move, the upper portions 34 and 35 of the head spread the lower portions 36 and 37 downwardly and outwardly into contact with the upper surface of plate 19. Sections 12 and 15 exert a downward force on inner legs 30 and 31 which because of the connection to the outer legs makes them fold around the lower edge of hole 38 to securely grip the under surface of plate 20. As sections 13 and 14 move downwardly simultaneously with sections 12 and 15, reinforcing elements 25 and 26 move with the inner legs of the feet to act as reenforcing members for them and aid in carrying out the feet of the rivet.

During the setting of the rivet, as head portions 34 and 35 and inner legs 30 and 31 are longer than the lower head portions 36 and 37 and outer legs 32 and 33, they exert forces on the lower head portions and the outer legs tending to draw them outwardly from the vertical axis of the rivet to the left and right thereof, as viewed in Figures 2 and 3. These forces in the head and feet act against each other because of the connection of the lower head portions and outer legs by stationary sections 10 and 11, and thus, as the rivet is set, plates 19 and 20 are drawn toward each other so that they are firmly gripped together. Furthermore, this same action forces the stationary sections outwardly against the inside of the hole so that they firmly grip both the inside and edges thereof. After the rivet is set, the upper portions of the head and the inner legs 30 and 31 form effective braces to prevent turning or loosening of the head or the feet when the rivet is placed under a strain. This bracing also prevents reverse movement of the movable portions of the rivet after the rivet has been set. Reinforcing elements 25 and 26 increase the strength of the rivet by both aiding in the action drawing plates 19 and 20 toward each other, as described hereinabove, and also by acting as supplementary braces to reinforce inner legs 30 and 31 after the rivet is set.

Thus, a rivet is disclosed which may be easily and economically manufactured. Furthermore, the rivet may be set quickly and easily by a single man who has access to only one side of the hole through which the rivet passes. Also, because of the construction of the rivet, there is a drawing

action between the head and the feet thereof which exerts great force in drawing the objects being riveted together, and the same portions of the rivet which effect this action form effective braces to prevent the turning or loosening of the head or feet of the rivet when they are placed under a strain.

Referring now to Figures 11, 12 and 13, another embodiment of the rivet is shown. This construction is formed from a single ribbon-like strip of sheet metal and includes a head generally indicated at 40, feet generally indicated at 41 and 42, movable sections 43 and 44, and stationary sections 45 and 46. As best shown in Figure 12, the ends of the ribbon-like strip of metal from which the rivet is formed are positioned in the angles formed by the upper and lower portions of head 40, and the material extends upwardly to the top of the head to form reenforcing elements 47 and 49 for the upper portions 49 and 50 of the head. From the top of the head the two portions of the strip extend downwardly to form movable sections 43 and 44 of the rivet, thence outwardly to form the inner legs 51 and 52 of the feet, and then are folded back on themselves to form the outer legs 53 and 54. From these points the portions of the strip extend upwardly to form the stationary sections of the rivet and thence outwardly and inwardly to a meeting point at the top of the rivet to form the rivet's head 40.

Referring to Figures 12 and 13, it may be seen that the upper portions 49 and 50 of the rivet's head are of substantially greater length than the lower portions 55 and 56 and that the inner legs 51 and 52 of the feet are of substantially greater length than the outer legs 53 and 54. These portions of the feet and head coact with the other portions of the rivet in the same manner as similar portions of the head and feet of the embodiment shown in Figures 1 through 3 to increase the strength and gripping action of the rivet.

As best shown in Figures 11, 12 and 20, the legs of the feet are preferably channel-shaped, each leg having its longitudinal edges flanged inwardly toward the vertical axis of the rivet. This materially strengthens the legs and assures bending at the desired points, the flanges being broken at the points where bending is desired as shown at the lower ends of the feet. Any straight section of the rivet may be strengthened by this or other means, and by weakening the reenforcing means at certain points, bending at these points is assured. Thus, the reenforcing of the legs or other straight sections of the rivet in the manner described materially strengthens the rivet and aids both in setting the rivet and in maintaining it in its set position, all as will be described hereinafter.

To set this type of rivet, it is placed in a hole 57 extending through a pair of plates 58 and 59 to be riveted together (Figure 12). When the head is struck, stationary sections 45 and 46 are held in their respective positions by the abutment of the lower portions 55 and 56 of the head against the edge of hole 57, while the movable sections are driven downwardly by the upper portions 49 and 50 of the head striking against reenforcing elements 47 and 48 and the upper ends of the movable sections. Movement of sections 43 and 44 downwardly causes the inner legs 51 and 52 to force the outer legs 53 and 54 into contact with the under surface of plate 59. During the setting of the rivet, reenforcing elements 47 and 48 in the head materially increase the strength of the upper portions 49 and 50 of the head, while at the

same time the flanges upon the edges of the legs of the feet materially strengthen them. Thus, a very strong drawing action is exerted by the upper portions of the head and inner legs upon the stationary sections of the rivet, as described with reference to the construction shown in Figures 1 through 3, because of the strength of the elements causing or supporting this action.

Thus, a rivet construction is disclosed which 10 may be readily formed from a ribbon-like strip of metal and which may be easily and quickly set by a single person having access to only one end of a hole in which a rivet is to be set. Furthermore, the rivet is so constructed and reenforced that it 15 has a very effective gripping action in drawing the plates 58 and 59 together as the rivet is set, and elements are provided which form strong braces to prevent the heads from being turned when the rivet is placed under a strain.

20 Referring now to Figures 14 through 18, another embodiment of the rivet is shown. This rivet is of tubular construction and is preferably formed from a flat metal sheet by the method described hereinabove with respect to the construction shown in Figures 1 through 3 and then rolled into its cylindrical shape. This rivet construction includes a head generally indicated at 60, a plurality of feet generally indicated at 61, a stationary cylindrical section 63, and movable 25 cylindrical sections 64 and 65. Head 60 includes a plurality of separate elements, each comprising upper and lower portions 66 and 67, respectively, which are angularly disposed with respect to each other, extend radially from the rivet, and connect stationary section 63 to the top of movable section 65. The stationary section 63 extends downwardly to the tops of the outer legs 68 of feet 61. The lower ends of legs 68 join the lower ends of the inner legs 69 which extend upwardly 30 to join the lower end of movable section 64. The legs of the feet are preferably of the same width, and thus, when they spread to form the lower end of the rivet, they extend radially from the rivet, all as will be described fully hereinafter.

ends of the rivet's feet. When the movable section 65 is moved sufficiently to free the feet 61, the head 60 of the rivet strikes the head 70 formed on movable section 64. This drives section 64 downwardly which, acting through the inner legs 69, drives the outer legs 68 into contact with the under surface of plate 75. The downward movement of the heads continues until the upper edge of cylindrically shaped member 71 (Figure 16) strikes upon the upper portions of head 70. As 10 the lower end of member 71 rests against the lower portion 67 of head 60, further movement of head 60 in a downward direction is prevented. Thus, by forming cylindrically shaped member 71 of the proper length, further downward movement of the head is prevented when the head fills the countersunk hole and the upper portions of the rivet are flush with the top surface of plate 74.

Referring to Figure 15, it may be seen that the stationary sections of the rivet are substantially shorter than the length of the hole in plates 74 and 75. Thus, both the outer legs and the inner legs, which are substantially longer than the outer legs, extend upwardly into the hole in plate 75. When the rivet is set, the upper portions of the outer legs are forced into contact with the lower edge of the hole extending through plates 74 and 75. By this type of construction, the drawing action described hereinabove with regard to the construction shown in Figures 1 through 3 is materially aided, and a tight grip between the sides of the rivet and the hole is assured.

Referring to Figures 15, 16 and 18, a flap 80 is provided on movable section 65 which locks the stationary and movable sections together after the rivet is set. This flap, which is preferably cut out of the inner movable section 65 (Figure 18) resiliently presses outwardly against movable section 64 before the rivet is driven. When the head 60 strikes head 70 during the setting of the rivet, the flap 80 resiliently moves out into a hole 81 cut through section 64 and locks sections 64 and 65 together so that they move as a unit during the remainder of the setting of the rivet (Figures 15 and 18). When the movable sections reach their final position as shown in Figure 16, the flap resiliently moves out into a hole 82 in stationary section 63. Thus, as the rivet is driven, the flap automatically locks the sections together, and when the rivet is set, it effectively prevents the movement of the movable and stationary sections with respect to each other.

Thus, a type of rivet is disclosed which may be driven by a single man having access to only one side of the hole in which the rivet is being set. Furthermore, this type of rivet construction may be driven into a countersunk hole, and its head is automatically stopped when its upper surface is flush with the plate in which the countersunk hole is positioned. Furthermore, the rivet is so constructed that it exerts an effective drawing action between its head and feet to draw the plates 74 and 75 together, and at the same time the stationary portion of the rivet is forced outwardly into contact with the sides of the hole and its edges. The rivet includes means to guide the end of the rivet into the hole and for preventing the fouling of the feet thereof with the sides of the hole during its insertion therein. The rivet also has means to lock the movable and stationary sections of the rivet together in their set positions, which acts as an

additional safeguard to prevent loosening of the rivet when it is placed under a strain.

Thus, an efficient and practical rivet construction has been disclosed in which the objects hereinabove set forth, as well as many others, are accomplished.

As many possible embodiments may be made of the mechanical features of the above invention and as many changes might be made in the embodiment above set forth, it is to be understood that all matter hereinabove set forth, or shown in the accompanying drawings, is to be interpreted as illustrative and not in a limiting sense.

15 I claim:

1. A rivet including a stationary portion and a movable portion, a plurality of U-shaped feet each having their upper ends connected to the lower ends of said movable and stationary portions, the inner legs of said feet being of considerably greater length than the outer legs thereof from their points of flexure whereby said inner legs, acting through said outer legs, exert a drawing action downwardly on the lower end 20 of said stationary portion as the rivet is set and move the outer legs to the under surface of the material in which the rivet is being set, and a collapsible head connected to the upper end of said stationary portion, said head including 25 upper and lower sections angularly disposed with respect to each other, the lower ends of said upper sections moving outwardly as said head collapses and thus, acting through the lower sections of said head, exerting a drawing action upwardly on said stationary portion as said rivet is set.

2. A rivet including a movable portion and a stationary portion, head means connected to said stationary portion, a plurality of U-shaped feet, each foot having its upper ends connected to said movable and said stationary portion, said feet being adapted to move outwardly when said movable portion moves downwardly with respect to 40 said stationary portion, and reenforcing members moving with said movable portion and extending downwardly within and to the ends of said U-shaped feet.

3. A rivet including a movable portion and a stationary portion, said movable portion including inner and outer sections, each section including a pair of flat members interconnected along one of their longitudinal edges, said stationary portion including a pair of flat members interconnected along one of their longitudinal edges, all of said members being in substantially parallel relationship to each other, a pair of U-shaped feet, each foot having its ends connected to one of the members of the inner movable section 50 and to one of said stationary members, and angularly shaped elements connecting the upper ends of the members forming said outer movable section to said stationary portion, said elements extending upwardly, first outwardly and then 55 inwardly, in planes radial to the vertical axis of said rivet to form triangularly shaped portions of the rivet with the upper end of the members forming the outer movable section.

4. In an article of the nature described, a pair 60 of inner movable members, a pair of outer stationary members, head means extending over the top of said members to interconnect said outer stationary members, the upper ends of said movable members contacting the under surface 65 of said head means, and a plurality of U-shaped

feet, each foot having its upper ends connected to said movable and said stationary members.

5. A rivet including a stationary portion and a movable portion, head means including a plurality of substantially straight members connected to said stationary portion, a plurality of U-shaped feet including substantially straight members connected to the lower ends of said movable and stationary portions, said feet being adapted to move outwardly when said movable portion moves downwardly with respect to said stationary portion, and means extending longitudinally of said substantially straight members to maintain said members substantially straight as said rivet is driven.

6. A rivet including an inner movable portion and an outer stationary portion, each of said portions including a pair of flat sections, all of said sections being substantially parallel to each other, a pair of U-shaped feet, each interconnecting the lower ends of a movable and a stationary section, head means including a pair of substantially straight members which extend outwardly and upwardly from the upper ends of said stationary sections in planes radial to the vertical axis of said rivet, and a pair of substantially straight members which extend inwardly and upwardly from the upper ends of said outwardly extending members to meet above the movable portion of said rivet, the upper end of said movable portion contacting the under surface of said head means.

7. A rivet including a stationary portion and a movable portion, said movable portion including inner and outer sections, a plurality of U-shaped feet, each foot having its ends connected to said stationary member and one of said movable sections, head means connected to said stationary member, and means formed on the other of said movable sections to prevent said feet from moving outwardly before the driving of the rivet is begun.

8. In an article of the nature described, an inner movable cylinder, an outer stationary cylinder, head means formed on said stationary cylinder, and a plurality of U-shaped feet having inner legs of substantially greater length than the outer legs thereof, the inner legs of said feet being connected to said movable cylinder and the outer legs of said feet being connected to said stationary cylinder, said feet being adapted to spread as said movable cylinder moves downwardly with respect to said stationary cylinder.

9. A rivet including a pair of movable portions and a stationary portion, said portions comprising three cylinders of increasing diameters positioned in telescopic relationship with respect to each other, a plurality of U-shaped feet, each foot having its ends connected to the lower end of said stationary portion and the outer of said movable portions, and head means connecting said stationary portion to the inner movable portion, said head means comprising a plurality of angularly shaped members including upper and lower sections which extend outwardly from the rivet in planes radial to the axis of the rivet and which form triangles with the upper ends of said inner movable portions.

10. A rivet including, a stationary portion and an inner movable portion, head means connected to said stationary portion, and a plurality of U-shaped feet movable laterally with respect to said movable portion having inner legs of considerably greater length than their outer legs from their respective points of flexure, the upper

ends of said inner legs being connected to said inner movable portion, and the upper ends of said outer legs being connected to said stationary portion, the upper ends of said inner legs, when said head means is in contact with the upper end of the hole in which the rivet is being set, being positioned within the hole a substantial distance from the bottom thereof, whereby, when said rivet is set, said inner legs exert a drawing action downwardly and outwardly on said outer legs, which drawing action acts through said stationary portion to firmly seat the rivet in the hole.

11. A rivet including, a stationary portion and an inner movable portion, collapsible head means connected to said stationary portion, and a plurality of U-shaped feet having inner legs of considerably greater length than their outer legs from their respective points of flexure, the upper ends of said inner legs being connected to said inner movable portion, and the upper ends of said outer legs being connected to said stationary portion, the upper ends of said inner legs, when said collapsible head means is in initial contact with the upper end of the hole in which the rivet is being set, being positioned within the hole a substantial distance from the bottom thereof, whereby, when said rivet is set, said inner legs exert a drawing action downwardly and outwardly on said outer legs, which drawing action acts through said stationary portion to firmly seat the rivet in the hole with the outer legs in snug surface contact with the material in which the rivet is being set, said collapsible head means including upper and lower connected sections angularly disposed with respect to each other and connected to said inner movable portion and said stationary portion respectively, said upper sections being of substantially greater length than said lower sections, the lower ends of said upper sections moving outwardly as said head means collapses and thus acting through the lower sections of said head means to exert a drawing action upwardly on said stationary portion as said rivet is set, whereby the lower sections of the head means are brought into snug contact with the other side of the material in which the rivet is being set.

12. In an article of the nature described, in combination, an inner movable cylinder, an outer stationary cylinder, head means formed on said stationary cylinder, a plurality of U-shaped feet having inner legs of substantially greater length than the outer legs thereof, the inner legs of said feet being connected to said movable cylinder and the outer legs of said feet being connected to said stationary cylinder, said feet being adapted to spread as said movable cylinder moves downwardly with respect to said stationary cylinder, and means to lock said cylinders with respect to each other when said rivet is in a set position.

13. In an article of the nature described, in combination, an inner movable cylinder, an outer stationary cylinder, collapsible head means connected to said stationary cylinder, said collapsible head means including upper and lower connected sections angularly disposed with respect to each other and connected to said inner movable cylinder and said stationary cylinder respectively, said upper sections being of substantially greater length than said lower sections, the lower ends of said upper sections moving outwardly as said head means collapses and thus acting through the lower sections of said head means

to exert a drawing action upwardly on said stationary cylinder as said rivet is set, and a plurality of U-shaped feet having inner legs of substantially greater length than the outer legs thereof, the inner legs of said feet being connected to said movable cylinder and the outer legs of said feet being connected to said stationary cylinder, said feet being adapted to spread

as said movable cylinder moves downwardly with respect to said stationary cylinder, whereby when said rivet is set, said inner legs exert a drawing action downwardly and outwardly on said outer legs which drawing action acts through said stationary cylinder to firmly seat the rivet.

LARS HEDSTRÖM.

CERTIFICATE OF CORRECTION.

Patent No. 2,333,930.

November 9, 1943.

LARS HEDSTRÖM.

It is hereby certified that error appears in the printed specification of the above numbered patent requiring correction as follows: Page 2, first column, line 54, for "outer" read --other--; and second column, line 10, for "22c and 23b" read --22c and 23a and 23b--; page 3, first column, line 20, for "and 49 for" read --and 48 for--; and second column, line 59, for "it to be" read --it is to be--; and that the said Letters Patent should be read with this correction therein that the same may conform to the record of the case in the Patent Office.

Signed and sealed this 4th day of April, A. D. 1944.

Leslie Frazer

(Seal)

Acting Commissioner of Patents.
